United States Patent Office

Des. 231,322
Patented Apr. 16, 1974

231,322

PULL FOR DOORS, DRAWERS AND THE LIKE

David F. James, Torrance, Calif., assignor to Norris Industries, Inc., Los Angeles, Calif.

Filed Aug. 9, 1973, Ser. No. 387,118

Term of patent 14 years

Int. Cl. D8—06

U.S. Cl. D8—166

FIG. 1.

FIG. 2.

FIG. 1 is a front perspective of a pull for doors, drawers and the like, showing my new design, as seen when turned at a slight angle about its long axis; and

FIG. 2 is a side elevational thereof.

I claim:

The ornamental design for a pull for doors, drawers and the like, as shown.
